RIVETING PROCESS

Walter Wallace Donald Warren, Montreal,
Quebec, Canada

Application July 16, 1949, Serial No. 105,168

1 Claim. (Cl. 78—46)

1
This invention relates to improvements in the art of riveting.

A particular feature of this invention is in the provision of a snap or die having an annular working face merging into a sharp pointed centrally protruding punch. The surface of the face may be either flat, concave or convex depending on the required shape of the rivet head.

Another feature of this invention lies in the provision of a relatively shallow indentation or cavity located in the central portion of the unheaded end of the rivet to be deformed for the reception therein of the protruding punch of the snap or die. The cavity is to be used in conjunction with the snap or die for centering same with respect to the rivet and for assisting in the flow of metal during the riveting operation.

Proceeding now to a more detailed description, reference will be had to the accompanying drawings, in which:

Fig. 1 is a sectional view showing a plurality of plates or work pieces riveted together in accordance with this invention. This view also shows one of the riveting dies or snaps which constitutes an essential novel feature of the invention.

Fig. 2 is a view showing how the snap or die is engaged with the end of the rivet during the early stages of the heading operation.

Fig. 3 is a plan view of the working face of one of the snaps or dies.

Fig. 4 is a sectional view showing a modified snap or die.

Fig. 5 is a sectional view showing another modified form of snap or die.

Conventional cold riveting, as heretofore practised, has been a machine operation performed in the shop by heavy pressure riveting machinery. No manual cold riveting either in a shop or in the field has been practical with the conventional cold riveting methods in sizes of $\frac{1}{2}$ " and over.

One advantage of the present invention is that, by virtue of the design of the snap or die provided in accordance with the invention, the force required to drive and form the head of a rivet is reduced to a sufficient extent to enable a cold rivet to be driven or headed by an operator using a hand pneumatic riveting gun equipped with the improved snap or die.

Another advantage is that, while the force required to drive and form the head is reduced to a sufficient extent to enable a cold rivet to be driven, by virtue of the design of the snap or die sufficient force is transmitted to expand the rivet shank to completely fill the rivet hole in the plates.

2
Another advantage of the invention is that the head formed by improved snaps or dies has less height in cramped positions than the conventional heads formed by the riveting operations now in use. In this connection it will be noted that the head formed by improved snaps or dies can have either annular, flat, concave or convex top surface surrounding a central inwardly extending cone-shape recess which tapers to a point or arc.

Another advantage of the invention is that the snap or die produces a type of rivet which may be advantageously used in place of fitted and/or turned bolts in both shop and field practice where adequate filling of the holes by the shanks of the rivets is necessary to ensure maximum shear and bearing values in a joint. In this connection, the present invention enables all rivets to come into stress at the same moment.

Another advantage of the present invention is that the improved type of rivet formed by the novel snap or die provided in accordance with this invention makes it possible, in most instances, to dispense with the heating of field and shop rivets, thus saving both labor and fuel.

Another advantage of the invention is that it makes possible the satisfactory cold driving of rivets made from steel, aluminum and various other metals and alloys.

Referring more particularly to the drawings, it will be noted that the improved snap or die 4, provided in accordance with this invention, is formed with a tapered face 5, of convex conical shape, merging with a central punch 6 which, in the present instance, is shown as having the shape of a circular cone which is sharply pointed at its outer end. However, it may be noted at this point that the shape of the cone 6 is subject to considerable variation. In this connection, it is pointed out that the punch 6 may have the shape of a pyramid, a star-shaped point or any other suitable shape which, when the punch is driven into a rivet cavity 7, will both centre the die and pierce the rivet and, at the same time, cause an outward flow of the metal of the rivet in a lateral direction and also a downward flow to fill the rivet hole completely.

In the use of this invention the plates or work pieces 8 which are to be riveted together are provided with rivet holes 9 through which the rivets 10 are passed. As here shown, each rivet is provided with a conventional head 11 against which the backing up or bucking tool is placed during the riveting operation.

As shown more clearly in Fig. 2, the rivet opening 9 provided in the plate 8, beyond which

the unheaded end of the rivet is initially projected, is countersunk at its outer end to provide a tapered recess 12. Fig. 2 also shows the unheaded end of the rivet drilled and countersunk in the central portion to provide a cavity 7. Cavity 7 is shown to be relatively shallow but greater in depth than the length of punch 6. The outer or upper section of the cavity is conically tapered; as indicated at 7a, toward a vertically disposed cylindrical mid-section 7b and the bottom section of the cavity is conically tapered to a point from the lower end of the cylindrical mid-section, as indicated at 7c. Cavity 7 is so designed as to cause an initial outward flowing of the rivet metal by the punch as the punch descends to the bottom of the cavity. After the punch has struck the conical bottom 7c of the cavity, the main upsetting operation begins. However, the initial flowing of the metal around the cavity, due to the descending pressure of the snap, relieves the shock of contact between the punch and rivet and facilitates the main upsetting operation of the unheaded portion of the rivet in its initial stage.

The best results are obtained when the depth of cavity 7 is such that the punch pierces the bottom of the cavity shortly after the beginning of the upsetting operation. The snap or die 4 is placed against the end of the rivet to be upset and is operated by means of a reciprocating percussion hammer which causes the punch 6 to penetrate the end of the rivet and to drive the metal of the rivet outwardly and downwardly. The working face 5 of the snap or die is highly polished so that, when this portion of the snap or die contacts the rivet, it allows the metal to flow laterally under the displacement action of the punch 6 and, at the same time, provides a compressing surface whereby the metal may be compressed onto the face of the adjacent plate 8 by circular rotation of the percussion hammer. In this connection it will be understood that the convex working surface 5 of the snap or die acts to press down the circular cantilever of metal surrounding the central opening formed by the metal displacing punch 6. The pointed tip of the punch press pierces the metal at the bottom of the cavity of the rivet and thereby decreases the resistance of the metal to the upsetting operation. The vertical force of the snap also causes the rivet metal to flow downwardly until it has completely filled the rivet hole in the plates.

In the modification shown in Fig. 4, the annular shoulder 6a serves to limit the outward flow of the rivet metal in a lateral direction.

Fig. 5 shows a further modification which consists of a concave annular face 5a which converge arcuately with the punch 6. The outward flaring portion of the concave face 5a is terminated in the annular shoulder 6a. When punch 6 is driven to penetrate the rivet in the cavity, the metal is caused to flow outwardly and

upwardly along the polished arcuate path of the snap face 5a and then downwardly along the flaring portion to the shoulder 6a. Shoulder 6a serves to limit the outward flow of the rivet metal in a lateral direction. The resulting rivet head formed by the concave faced snap has an annular convexly curved top surface surrounding a central inwardly extending cone-shaped cavity.

I claim:

A riveting process which comprises forming, in the end of the rivet shank remote from the head, a central punch receiving cavity having a conical inner portion tapering to a point in the direction of the head of the rivet, an intermediate cylindrical portion and an outer conical portion flaring outwardly from said intermediate portion, the depth of said cavity being predetermined with reference to the thickness of the work so that, when the rivet is passed through the rivet receiving opening in the work with the head of the rivet bearing against one side of the work, a portion of the rivet shank lying inwardly of the inner end of the cavity will project beyond the opposite side of the work, passing the rivet through the said work until the head of the rivet bears against one side of the work and then heading the cavity containing end of the rivet shank by forcing thereagainst a heading die presenting a central punch tapering to a point and surrounded by an annular working face inclining outwardly and upwardly from the base of the punch, said punch being of a length less than the total length of said cavity and having a base diameter greater than the diameter of the inner end of the outer conical portion of the cavity, said die being initially arranged with the punch fitted in the outer conical portion of the cavity and with the working face of the die bearing against the end surface of the shank bordering the cavity, and forcing of the die against the cavity containing end of the shank until the material of the shank at the inner end of said cavity is pierced by the punch.
